UNITED STATES PATENT OFFICE.

SAMUEL I. DERR, OF EMAUS, PENNSYLVANIA.

CLAMPING AND HOLDING MEANS FOR SHOE-UPPERS.

1,166,335.

Specification of Letters Patent. Patented Dec. 28, 1915.

Application filed September 17, 1914. Serial No. 362,193.

To all whom it may concern:

Be it known that I, SAMUEL I. DERR, a citizen of the United States, and a resident of Emaus, in the county of Lehigh and 5 State of Pennsylvania, have invented a new and Improved Clamping and Holding Means for Shoe-Uppers, of which the following is a full, clear, and exact description.

This invention relates to improvements 10 in clamping devices for shoe uppers and has for an object to provide a device for clamping and holding uppers preparatory to marking the spaces for buttons thereon.

A further object in view is to provide 15 an improved construction which will engage and hold the uppers properly in position while the same are being marked.

Another object of the invention is to provide a holding device for the button 20 lap and outside quarter of a shoe which has a double movement, one for grasping the outside quarter and button lap and the other for forcing the outside quarter and button lap against a suitable support where 25 it may be spread and arranged even preparatory to the marking operation.

A still further object of the invention is to provide a holding device which allows 30 the knee and feet to operate the mechanism while the hands of the operator may be used for smoothing and straightening the uppers and also for the marking operation.

In the accompanying drawings—Figure 1 is a top plan view of an embodiment of the 35 invention, the uppers of a shoe being used in connection therewith; Fig. 2 is a view similar to Fig. 1 showing the uppers folded and ready for the marking operation; Fig. 3 is a front view of the structure shown in 40 Fig. 1; Fig. 4 is a side view of the structure shown in Fig. 3; Fig. 5 is a fragmentary sectional view through Fig. 1 approximately on line 5—5, the same being shown on an enlarged scale; Fig. 6 is a fragmentary sectional view through Fig. 2 on line 6—6, 45 the same being on an enlarged scale.

Referring to the accompanying drawings by numerals, 1 indicates a table which may be made of any desired material, but preferably of metal cast with a pair of depending lugs 2 and 3, and with a hollow depending guide 4. The table 1 may be secured to any desired kind of support and at any height, but preferably at the proper height 50 for an operator's knee to strike against the

pressure plate 5 (Fig. 3) so that the operator may by moving his knee to one side rock the rock shaft 6 through the rod 7 which is secured to the rock shaft 6 by a suitable set screw 8. The rod 7 is bent at 60 right angles as shown in Fig. 3 and a portion projected through a tubular enlargement 9 arranged on the projection or bracket 10 of rock shaft 6. By sliding the rod 7 back and forth through the enlargement 9 the plate 5 may be adjusted to any desired position so as to be properly engaged by the operator's knee. A set screw 11 is provided for rigidly clamping plate 5 to bar 7. The rock shaft 6 is pivotally supported 65 by screws 12 and 13 (Fig. 4) which extend through the lugs 2 and 3, and into suitable sockets in the rock shaft 6. The rock shaft 6 in addition to the projection or socket 10 is provided with an enlargement 14 having 70 a bored out or hollow portion for a shaft 15. Shaft 15 may be clamped in any adjusted position by a suitable set screw 16 so as to properly engage the link 17 (Fig. 6) which is connected with lug 18 of a pivotally 75 mounted catch 19. The catch 19 is provided with a lug 20 whereby notches 21 and 22 are presented which receive the end 23 of the jaw or clamping bar 24. Co-acting with the jaw or clamping bar 24 is a second jaw 80 or clamping bar 25 hereinafter fully described. The catch 19 is pivotally mounted at 26, the pivotal mounting consisting of a suitable pivotal pin extending through the catch and also through a bifurcated extension 27 formed integral with the guide 4 and top 1. The catch 19 is provided with a depending lug 28 having a suitable notch 85 therein for receiving the end of spring 29, the opposite end of spring 29 fitting into 90 a suitable notch in the guide 4 whereby the lower end of the catch 19 is given a tendency to swing away from guide 4 and the upper end given a tendency to swing in 95 an opposite direction.

The jaws 24 and 25 are designed to cause the upper of a shoe to be gripped or held in a predetermined position as shown in Figs. 1, 2, 5 and 6. When the device is in the position shown in Figs. 3 and 4 the 100 same is in operative position so that the front end of the button lap and outside quarter may be inserted beneath projection 30 on jaw 25. Arranged on jaw 25 below projection 30 is a bar 31 secured in place 105 110

by screws or other suitable means, which bar is provided with an aperture for accommodating the awl 32, which awl is carried by jaw 24 and passes through a suitable aperture in extension 30. After the quarters have been inserted between projection 30 and bar 31, as shown in Fig. 1, jaw 24 is lowered to the position shown in Fig. 5 and then the uppers are turned to the position shown in Fig. 2, after which both jaws 24 and 25 are lowered to the position shown in Fig. 6 and held in that position until the operator with his hands straightens the various parts as shown in Fig. 2 and then with one hand marks the place where the buttons are to be placed.

In order to make the parts operate as just described, jaw 24 is fitted on to the bar 33, which bar is provided with an enlarged upper end 34' so that jaw 24 cannot accidentally become disconnected from bar 33. Jaw 25 is rigidly secured to a sleeve 34 in any desired manner so as to be moved upwardly and downwardly therewith. Bar 33 is slidingly fitted into sleeve 34 and sleeve 34 in turn slidingly fits into the guide 4. Sleeve 34 is prevented from rotating by a screw or other projection 35 extending into a slot 36 formed in the sleeve. This will allow the sleeve to freely reciprocate, but will not allow any pivotal movement thereof. If desired a spline or other suitable device could be provided between sleeve 34 and bar 33 for preventing bar 33 from rotating though ordinarily this is not necessary as the awl 32 will prevent such rotation, said awl having a portion thereof continually in the aperture formed in extension 30. Awl 32 is held in place by a suitable set screw 37, and is positively prevented from moving upwardly when pressed against the leather of the uppers by the head of a suitable screw 38 (Fig. 6). From Fig. 6 it will be noted that the lower end of the awl is designed to extend through bar 31 and into a recess or depression 39 arranged in the table 1. Rigidly secured to the lower end of sleeve 34 is a combined operating lug and stop 40, the securing means preferably being threads, while the lower end of bar 33 has rigidly secured thereto, as for instance by threads, a stop and operating member 41. Stop 40 has connected therewith a spring 42, while stop 41 has connected therewith a spring 43. Springs 42 and 43 are also connected with suitable hooks on table 1 as clearly shown in Fig. 3 so that the parts will be resiliently supported in the position shown in Figs. 3 and 4, and will be moved back to said position when moved therefrom. Preferably the springs are continually under a slight tension even when in the position shown in Figs. 3 and 4. Connected with the lower end of bar 33 is a rod 44, which rod is con-

nected by a suitable clamp 45 with a second rod 46, which second rod is hooked into or otherwise pivotally connected with a treadle 47. Whenever treadle 47 is moved downwardly rod 44 will be moved downwardly until jaw 24 engages jaw 25, and then both jaws together with rod 44 and sleeve 34 will move downwardly until the parts assume the position shown in Fig. 5. When treadle 47 is released the parts will automatically rise to the position shown in Fig. 3 under the action of springs 42 and 43. In Fig. 6 it will be noticed that a buffering member of rubber or other suitable material 48 is provided for cushioning the upward movement of the respective parts.

When the uppers of a shoe are spread out as shown in Fig. 1 the outside quarter and button lap may be properly arranged, and while thus arranged the awl 32 is forced through the various parts (Fig. 5) and thereby holds the same properly in place regardless of what may be done thereafter. When attempting to hold the parts of the uppers in place by hand oftentimes the parts slip, and in fact usually the parts slip so that when a pencil or other marking tool is inserted through the buttonholes 49 the same will not promptly mark the quarters for the buttons. If the buttons are not properly placed there will be a puckering action when the shoe is placed upon the last. As the parts may be easily placed in proper position when the same are spread as shown in Fig. 1 it is evident that if held in such position while folding the various parts so as to occupy the position shown in Figs. 2 and 6 a proper marking may easily be had by inserting a marking tool into the various buttonholes 49.

It is to be noted that the present invention presents means which in effect allows one operator to do the work required by four hands, and with the mechanical hands the present construction rigidly holds the parts in correct position and positively prevents any slipping during the straightening of the button lap and other parts of the uppers, and also prevents any slipping or movement of the parts while the marking operation is taking place.

From Fig. 5 it will be noticed that when the treadle 47 is first depressed awl 32 will pierce certain parts of the uppers and jaw 24 will be clamped tightly against jaw 25, while jaw 25 will be pressed against lug 20, the same resting in notch 21. By reason of lug 20 the parts cannot move downwardly from the position shown in Fig. 5 until the knee resting against plate 5 has been moved to one side, whereupon rock shaft 6 will be moved and catch 19 moved from beneath jaw 25, whereupon the continued downward pressure on treadle 47 will cause the jaws 24 and 25 to move from the position shown

in Fig. 5; whereupon the knee of the operator will release plate 5 and catch 19 will automatically move to the position shown in Fig. 6 under the action of spring 29. After 5 the parts are in the position shown in Fig. 6 the uppers are smoothed out as shown in Fig. 2 and then marked. When the marking operation has been completed and it is desired to remove the uppers from the device, the knee of the operator is moved until 10 catch 19 is disengaged from the jaw 24, whereupon springs 42 and 43 will move the various parts to the position shown in Fig. 4. The device is then in position for 15 another operation.

What I claim is—

1. In a device for holding the uppers of shoes while the same are being marked for receiving buttons, a supporting table, a pair 20 of jaws for engaging said uppers, means for causing the jaws to come together, said means being adapted to move both of said jaws against said table, a lock for locking said jaws against said table whereby the 25 uppers are held in position during the marking operation, and means operable by the knee of the operator for releasing said lock.

2. In a device of the character described, 30 a pair of jaws, means for causing said jaws to come together and then force both of the jaws against a supporting table, and awl extending from one of said jaws designed to be thrust through the uppers of a shoe when said jaws are brought together, and means 35 for locking the jaws in their lowered position when moved thereto.

3. In a device for holding the uppers of shoes while the same are being marked for receiving buttons, a supporting table, a pair 40 of jaws, a gripping member carried by one of said jaws, means for causing said jaws to come together and said gripping member to grip the uppers of a pair of shoes, said means being adapted to move both of said 45 jaws against said table, and a catch for locking said jaws against said table, whereby said uppers are held in proper position during the marking operation.

4. In a device for holding the uppers of 50 shoes while the same are being marked for buttons, a table on which the uppers are to be laid during the marking operation, a jaw formed with a notched-out portion for receiving part of the uppers, a second jaw arranged above said first mentioned jaw, said second mentioned jaw having an awl designed to extend through said notched-out portion of the first mentioned jaw and through the part of the upper arranged in 55 said notched-out portion, a reciprocating bar for moving said upper jaw against the lower jaw, means for movably supporting said lower jaw whereby said upper jaw may move the lower jaw against said table, and a 60 catch engaging said upper jaw for holding

the same against movement after the upper jaw has moved the lower jaw against said table.

5. In a device of the character described, a supporting table, a reciprocating sleeve arranged to move vertically through said table, a rod extending through said sleeve, a jaw secured to said sleeve, said jaw being formed with a notch and an aperture, an apertured bar arranged at the lower edge of said notch 70 and overlapping the notch so as to make a substantially grooved structure for receiving part of the uppers of a shoe, a second jaw arranged above said first mentioned jaw and connected with said rod, an awl mounted in 75 said second mentioned jaw and extending through the aperture in said first mentioned jaw and through the aperture in said bar as well as through the part of the upper arranged in said groove so as to positively prevent any slipping of the various parts of the upper, a catch for holding said first mentioned jaw spaced from said table, said rod being operable to move said second mentioned jaw downwardly against said first 80 mentioned jaw and said awl through both of said apertures, and operating members for disengaging said catch whereby said jaws may move downwardly against said table, said catch being provided with a resilient 85 member for moving the same over into engagement with said jaws after the same have engaged the table so as to lock the jaws against the table.

6. In a device of the character described, 90 gripping members for gripping an upper and holding the same against accidental shifting, a foot operated member for moving said means downwardly, a table arranged to limit the downward movement of said gripping members, a catch for locking said gripping members against said table, a rock shaft formed with an extension engaging said catch for disengaging the same from said gripping members, and a knee operated 95 member extending from said rock shaft whereby when said knee operated member is moved in one direction the catch will be disengaged.

7. In a device of the character described, 100 a table, a pair of supporting extensions arranged on said table on the lower face thereof, said table being formed with a depression in the upper face thereof, a guiding member extending downwardly from said table, said 105 guiding member being formed hollow, a rock shaft supported by said extensions, means adapted to be operated by the knee of an operator for rocking said rock shaft, a spring pressed pivotally mounted catch connected 110 with said rock shaft and adapted to be moved in one direction thereby against the action of said spring, a sliding sleeve arranged in said guiding member, a sliding rod arranged 115 in said sleeve, a treadle connected with said 120

rod for moving the same downwardly, a jaw secured to said sleeve arranged with part of the same normally above said catch whereby the jaw is prevented from moving downwardly against said table, a jaw secured to said rod, a spring for normally moving said rod upwardly whereby said second mentioned jaw is spaced from said first mentioned jaw, a stop for limiting the upward movement of said rod, said first mentioned jaw being formed with a notch in one end and an aperture arranged above the notch, an apertured bar arranged below said notch, and an awl secured to said second mentioned jaw with one end normally in said first mentioned aperture, said apertures being in alinement whereby when said second mentioned jaw is moved downwardly against said first mentioned jaw said awl will pierce the part of an upper arranged in the notch in said first mentioned jaw, said treadle being designed to move both of said jaws

downwardly so that the first mentioned jaw will press the second mentioned jaw against the table when said rock shaft moves said catch away from said jaws, said depression in said table receiving the lower end of said awl.

8. In a device of the character described, a table, means for gripping part of an upper for holding the various sections of the upper against independent movement, means operable by the foot for moving said gripping means downwardly against said table, locking means for holding the gripping means against the table, and means operable by the knee for releasing said locking means.

In testimony whereof I have signed my name to this specification in the presence of two subscribing witnesses.

SAMUEL I. DERR.
